CATHODE-RAY CODING TUBE

William M. Goodall, Oakhurst, N. J., assignor to
 Bell Telephone Laboratories, Incorporated, New
 York, N. Y., a corporation of New York

Application July 3, 1948, Serial No. 37,035

9 Claims. (Cl. 315—21)

1

This invention relates to cathode ray tubes and more particularly to cathode ray tubes employed for representing instantaneous amplitudes of complex wave forms by means of the code groups of signaling conditions.

In the prior art cathode ray tubes employed for representing instantaneous amplitudes of complex wave forms an electron beam was employed which beam is focused in the form of a small point on a target plate. The beam is deflecting in one direction under control of the amplitude of the complex wave form and is caused to move across the target or aperture plate in another direction across apertures in the target. The target is formed so that the beam in sweeping across the target will form code groups of pulses of signaling conditions depending upon the apertures through which the beam passes.

In such a tube it is first necessary to position the beam in one direction and then maintain the position in this direction while the beam is moved in another direction. Thus in order to form a code group it is necessary to successively move the beam into different directions. All these operations require appreciable time and the code is never complete until a beam completely sweeps across the entire target for a given signal amplitude.

The object of the present invention is to provide an improved cathode ray tube which operates at a high rate of speed and which continuously provides at its output terminals a complete code group of signaling conditions representing the instantaneous amplitude of a complex wave form.

One feature of this invention relates to a coding tube which operates continuously to supply to the output circuit code groups of signaling conditions under control of an applied complex wave form in which the code groups of signaling conditions are all changed simultaneously and which all represent the instantaneous amplitude of complex wave forms at substantially all times.

A feature of this invention relates to a translating and coding tube in which it is necessary to move the beam in either direction along one line which usually forms one of the axes of the output electrodes.

A feature of this invention is to provide a translating or coding tube which will form or generate the same code group of signaling conditions for amplitudes beyond or in excess of the limits of the normal operating range of the tube which are the same as the codes representing

2

the limiting amplitudes of the normal operating range.

Another feature of the invention relates to a modified target in which some apertures in addition to the end apertures are elongated to suppress noise, to clip, compress or otherwise modify the complex wave form or the signals transmitted representing it.

Another feature of this invention relates to 10 auxiliary beam positioning apparatus comprising additional apertures in the target and means and interconnections for the deflecting beam to cause the beam to occupy a position over a given group of apertures and to prevent the beam from occupying a position between groups of apertures representing different codes.

Another feature of this invention relates to the cathode ray tube in which the electron beam is in the form of a sheet or plane electron which is focused by means of apertures and other beam forming elements in a narrow line across target plate. Deflecting means are provided for moving said beam relative to the aperture plate so that it passes through different code groups of 25 apertures of said target plate.

Another feature of the invention relates to a plurality of collective electrodes arranged behind apertures in said aperture plate to collect electrons passing through said apertures of the aperture plate or target.

30 Briefly, in accordance with the present invention the cathode ray tube comprises a source of electrons, beam forming and focusing elements for forming a flat beam of electrons and focusing them in a narrow line upon a target or aperture plate, deflecting means for deflecting the beam over said aperture plate, and an aperture plate provided with code groups of apertures formed therein.

40 While the apertures may be formed in the aperture plate in any predetermined manner according to any desired code or in a random fashion, in the specification embodiment set forth herein the apertures in the aperture plate are arranged to form a binary number system or code wherein the apertures are arranged in columns and each aperture in the first column represents the magnitude of one unit of amplitude of a complex wave form. Each aperture in

45 the next column represents two units in the instantaneous magnitude of the complex wave form. The apertures in the third column represent four units and each aperture in the fifth column represents eight units, etc. An auxiliary group of apertures and an auxiliary electrode behind these

auxiliary apertures are arranged to prevent the electron beam from coming to rest between two groups of apertures in the aperture plate.

The foregoing objects and features of this invention, the novel features of which are specifically set forth in the claims appended hereto, may be more readily understood from reference to the attached drawings in which:

Fig. 1 illustrates an exemplary form of cathode ray tube for representing instantaneous amplitude of the complex wave form by means of code groups of signaling conditions; and

Fig. 2 illustrates a modified target.

Such types of signaling circuits and apparatus are frequently called code modulation systems and the code employed in the exemplary embodiment set forth herein is sometimes called a binary code.

A tube of the type described herein is suitable for use in combination with the other circuits in my copending application Serial No. 67,211 filed in the United States Patent Office December 24, 1948.

The coding tube in accordance with the present invention is also suitable for use in combination with the other systems and circuits described in an application of J. C. Schelleng, Serial No. 677,667 filed June 19, 1946, now Patent 2,453,461, granted November 9, 1948 disclosure of which application and patent is also hereby made a part of the present application as if set forth herein in full.

As shown in Fig. 1 of the drawing the tube comprises an evacuated envelope 10 which may be of metal, glass or other suitable material including combinations of metal, glass or other suitable materials usually employed in the construction of evacuated electron tubes and devices. Cathode 11 of the tube provides a suitable source of electrons when heated to the proper temperature by means of the heating element supplied by suitable power through transformer 18 in the usual manner.

Three beam forming elements 12 are shown in the drawing. The beam forming elements may be of any desired or suitable number and may be of any desired shape or configuration. These elements and apparatus herein provided are connected to suitable sources of accelerating and beam forming and focusing potentials such as sources 28 and 27. Sources 27 and 28 are illustrated as batteries in the drawing and may comprise rectifiers, filters, or any other suitable power sources or generators.

In accordance with the present invention the beam forming electrodes 12 are arranged to form a wide beam or plane of electrons of very small thickness which is focused upon the target 17. The beam forming elements 12 may be equipped with apertures in the form of slits instead of small holes as in the usual case so that these beam forming electrodes will function analogous to cylindrical lenses instead of analogous to circular or spherical lenses as in the usual cathode ray tube wherein the electrons are focused to a small spot or point on the screen or target.

The beam forming members as shown on the drawing are intended to represent or include magnetic beam forming focusing fields, coils and related elements and apparatus. Thus the beam forming and focusing may be electrostatic, electromagnetic or a combination of both types of electron control means.

Target 17 is provided with a plurality of apertures arranged in columns and rows as shown

in the drawing. In accordance with the exemplary embodiment set forth herein the apertures in target 17 are arranged to form the desired code when the beam impinges upon the target in different positions.

The coding and translating tube described herein is arranged to represent the amplitude of the complex wave form by means of code groups of signaling conditions. Each code group comprises a plurality of independent signals each signal of which may be any one of a plurality of different signaling conditions.

In the exemplary embodiment described herein the target is arranged to represent the amplitude 15 of the complex wave form at rapidly recurring instants of time by code groups of five different signals. These signals may be of either one or the other of two different signaling conditions. The invention is not limited to code groups of 20 five different signals but may employ code groups of any number of signals each of which may comprise any number of signaling conditions.

In order to more readily describe and follow the various signaling conditions these two signaling 25 conditions are frequently called a "marking" signaling condition and a "spacing" signaling condition; they are some times called "on" signals and "off" signals; other times they are called signals of current and no-current; other times they are called signals of one polarity, say positive, and signals of a negative polarity or voltage. These signals in being transmitted through the various circuits and apparatus of the system may change their form from current 30 to no-current, from positive to negative, etc. As a result it is frequently more desirable to refer to them as "marking" signals or "spacing" signals or "on" signals or "off" signals.

It is to be understood that the target may be 40 arranged to employ more signal elements in each code combination and that the signal elements of these code combinations may comprise any one of more than two different signaling conditions. However, in order to more readily understand the invention the code employed in the exemplary embodiment described herein is one in which each of the elements may comprise either one or two different signaling conditions in the exemplary embodiment set forth herein.

As shown in the drawing, the aperture plate 55 17 is arranged to form code groups of signaling conditions in accordance with binary number system. The first column of apertures 35 represents one unit. When the beam passes through an aperture in this column and some electrons fall upon the electrode 25 it represents one unit of the amplitude of the complex wave form. When the beam passes through an aperture in the column 34 it represents two units of the amplitude. When the beam passes through an aperture in column 33 it represents four units. Likewise each time it passes through an aperture in column 32 it represents eight units and when it passes through an aperture in column 31 it represents sixteen units of the amplitude of the complex wave form. The total amplitude of the complex wave form is thus represented by the sum of the magnitudes represented by the apertures through which the beam passes.

Deflecting plates 13 and 14 are provided and connected through transformer 19 to a source of signals or complex wave forms to be represented by the code groups or signaling conditions. These plates are arranged to deflect the

beams vertically as shown in the drawing. While the beam is shown deflected in the drawing by the electrostatic plates 13 and 14, these plates may be replaced by electromagnetic deflecting coils and means as is well understood in the art. In addition, a combination of both types of deflection may be employed when desired. Also as shown in the drawing, the signals are balanced with respect to the main anode voltage by means of transformer 19. Where desired, these applied signals may be balanced with respect to any electrode or they may be unbalanced.

As shown in the drawing, the beam is focused in a horizontal line across the target plate 17 and deflected vertically, that is, at right angles to the line of the beam under control of the applied signals. When the signals are of a minimum amplitude the beam will be deflected toward the lower part of the target plate. When the amplitude of the complex wave form is near the average value the beam will be near the middle of plate 17. When the amplitude of the complex wave form approaches a maximum the beam is moved up near the top of target plate 17.

When the beam is in its lowest position the beam will not pass through any apertures in the aperture plate. It may be desired to extend the plate somewhat further downward so that for all amplitudes less than a predetermined minimum the same code combination, in which the beam does not pass through any of the apertures, is generated in the output circuits of the tube. In the first position above this position the beam will pass through the lowermost aperture in column 35 thus indicating one unit of amplitude of the complex wave form above the minimum amplitude.

The apertures in the target plate are described herein as arranged in rows and columns. It is evident that by rotating the tube through 90 degrees the rows become columns and the columns rows so that the rows and columns are interchangeable.

Also in the exemplary embodiment set forth herein, an aperture plate is provided in combination with collecting electrodes behind the apertures. It is evident that an equivalent group of properly shaped and proportioned collecting electrodes can be employed when desired.

In the second position from the bottom the electron beam will pass through an aperture in the second column 34 thus indicating two units of amplitude above the minimum. In the third position the beam will pass through an aperture in the first column 35 and another aperture in the second column 34 thus indicating three units of amplitude. In the fourth position the beam will pass through an aperture in the third column 33 indicating four units of amplitude. In each one of the succeeding positions the beam will pass through apertures in the various columns indicating the units of amplitude of the applied complex signal wave. As is pointed out above, the plate may be extended an appreciable distance below the lowermost position of apertures so that should the beam be deflected downward to a greater extent than normal the same code combination as the last lowermost position wherein the beam does not pass through any apertures will still be maintained on the output electrodes.

When desired, additional elongated apertures may be provided in the target plates which may be extended by greater or lesser amounts as may be desired. These additional elongated apertures may be positioned near the center of the plate to

effect noise suppression or at any other intermediate position for other special purposes including limiting, clipping, compression, expansion, etc.

Fig. 2, for example, shows a modified target plate in which one set of code apertures has been elongated so that so long as the beam remains in this small center range the same output code is applied to the output electrodes. In this manner small noise potentials or voltages are all represented by the same code and thus effectively suppressed. However, when signals having a greater amplitude than the normal noise amplitude are applied to the deflecting system of the tube they will cause the tube to operate in the manner described above and transmit or generate code groups representing the amplitude of the applied signal wave. As shown in Fig. 2, the end apertures are also elongated so that the tube will operate as described above when abnormally large signaling amplitudes are applied to the tube.

When desired, the aperture may be made to become progressively larger or progressively smaller as the amplitude of the applied signaling wave is increased. In the first case, the applied wave form is effectively compressed so that a larger signal amplitude may be represented by a given number of codes. In the second case, the complex wave form is effectively expanded.

Likewise, the uppermost apertures may be extended for an appreciable distance above the last normal position of the beam so that in case it is deflected in an abnormal amount upward the same code combination wherein the beam passes through an aperture in each one of the coding columns will be continued even for the abnormal deflection of the beam by an abnormally strong signal wave applied to the deflecting plates 13 and 14.

It should be noted that the proper biasing voltages as well as the signal voltages, described above, are applied to the deflecting plates 13 and 14 so that the voltages of these plates do not interfere with and may aid in the focusing of the electrons in a narrow line upon the target 17.

The electrons which pass through apertures in the target plate in accordance with any suitable type code such as that described above, will fall upon the collecting electrodes 21 through 25, inclusive, positioned behind the respective columns of apertures 31 through 35, inclusive. When electrons fall upon these collecting electrodes they cause a change of potential of the respective electrodes. If the electrodes act as normal collecting electrodes, their potential will fall or become more negative in response to the electrons which fall on these elements. If, on the other hand, the elements 21 through 25, inclusive, act as secondary emitters then when the primary electrons from the beam impinge upon them they will become more positive.

In either case, it is evident that the potential or voltage of these electrodes is one value when the electron beam does not fall upon them and is another value when the beam does fall upon them. Thus, the voltage of these electrodes continuously represents the magnitude of the applied complex wave form applied to the deflecting plates 13 and 14. Thus, except for the time during which the beam is passing from one row of apertures to another, the potential of the output electrodes 21 through 25, inclusive, continuously represents the magnitude of the applied complex wave form. It should also be noted

that the complete code group of potential or signaling conditions is simultaneously applied or appears on all of the output electrodes.

In order to prevent the beam of electrons from remaining between two rows of apertures representing two different amplitudes and thus even causing no potential on the output leads or causing potentials in accordance with two different codes to be applied to the output leads and in order to reduce the time required for the electron beam to be shifted from one row of apertures to the next an additional set of column apertures 33 is provided in the target plate 17 and additional collecting element or electrode 26 is provided behind these additional apertures. These additional apertures, as illustrated in column 30, are provided between the rows of coded apertures for columns 31 through 35, inclusive. Thus, if the beam of electrons tends to fall between two rows of the coded apertures in response to the applied signals a portion of the electrons will pass through one of these auxiliary apertures and cause the collecting element 26 to become more negative, for example, due to the electrons received by it. This element is connected to one of the auxiliary sets of collecting plates 15 and as a result the deflecting plate 15 tends to become more negative and tends to move the beam downward so that it will no longer rest between the two rows of coding apertures, instead the beam or the major portion thereof will pass through the apertures in the next lower row.

If, however, the signal changes sufficiently then the beam will move very rapidly up to the next row when the signal overcomes the effect of the potential applied to the auxiliary deflecting elements 15 and 16. The auxiliary apertures, collecting element and the auxiliary deflecting element of the tube described above are frequently called quantizing elements because they tend to cause the beam to occupy discrete positions on the target plate 17 and thus tend to represent the magnitude of the incoming signal by any one of a plurality of different discrete codes representing a particular discrete amplitude of the incoming signal. In other words, the incoming signal is represented by codes of signaling conditions applied to the output electrodes of the tube which do not represent a function which may be represented by a smooth curve but one having any one of a plurality of separate and distinct amplitudes.

It is, of course, apparent that the feedback connection or circuit from the auxiliary element 26 to the auxiliary deflecting plates 15 and 16 may include suitable types of amplifying equipment, centering equipment and other control equipment necessary to secure the desired control of the electron beam so that the major portion of the electrons of the beam will always pass through some one row of coded apertures in the aperture plate 17. As a result, the output voltages of the output electrodes 21 through 25, inclusive, continuously and at all times develops a group of coded signaling conditions which represent the magnitude or amplitude of the applied complex wave form.

What is claimed is:

1. A continuous coding tube for continuously representing the magnitude of an applied signal wave by means of code groups of signaling conditions each of which may be any one of a plurality of different potential conditions comprising a source of electrons, electron beam forming elements for forming a thin sheet of electrons, a

coding apertured target plate having coded apertures arranged in rows across said aperture target plate, focusing means for focusing the electrons of said beam in a narrow line on said target parallel to said rows of apertures, signal responsive means and means controlled by said signal responsive means for directing said beam of electrons to one of the rows of apertures on said target plate representative of a magnitude of the applied signal wave.

2. A continuous coding tube for continuously representing the magnitude of an applied signal wave by means of code groups of signaling conditions of one of a plurality of different potential conditions comprising a source of electrons, electron beam forming elements for forming a thin sheet of electrons, an apertured target having coded apertures arranged in rows across said aperture target, focusing means for focusing the electrons of said beam in a narrow line of said target parallel to said rows of apertures, signal responsive means, means controlled by said signal responsive means for directing said beam of electrons to one of the rows of apertures on said target representative of a magnitude of the complex wave form, auxiliary apertures in said target, an auxiliary electrode behind said auxiliary apertures, auxiliary deflecting means, and connections between said auxiliary electrode and said auxiliary deflecting means for preventing the major portions of said electron beam from falling between two of said rows of apertures.

3. In an electron discharge tube a source of electrons, means for forming a beam of said electrons and focusing said electrons in a narrow line, a coding target having a plurality of coded areas arranged in rows and columns, one of which is parallel to the line of electrons, signal responsive apparatus, means for applying signals to said signal responsive apparatus, deflecting means for deflecting said line of electrons in a direction perpendicular to the said direction of said line of focused electrons, and connections between said signal responsive apparatus and said deflecting means for deflecting said beam of electrons an amount which is proportional to the magnitude of said applied signals.

4. In an electron discharge tube a plurality of target areas associated with output electrodes arranged in rows and columns in which all said areas in one row differ in length in the direction perpendicular to said row from the areas in other rows, electron beam forming and focusing elements associated with said tube for forming a beam and focusing it in a narrow line across rows of said apertures and apparatus responsive to receiving signals for deflecting said beam at right angles to said line and said elongated direction.

5. A coding tube having means for generating a cathode beam, a coding target for said beam, means for deflecting said beam in relation to signal amplitudes to cause it to impinge on various portions of said target, thereby producing code signals related to said deflection signal amplitude, the number and arrangement of said coding portions and the deflecting means being so arranged that each recognizably different signal amplitude within a normal range is translated into a unique pulse code group, said target being characterized in this, that the width of each end portion of said target, measured in the direction of the beam deflection, substantially exceeds the width of every other portion, where-
75 by any abnormal extreme peak of said signal,

producing extreme deflections, is translated into the same code as an extreme peak within the normal amplitude range.

6. A cathode ray tube and associated circuits for coding instantaneous values of an input wave into 2^n codes where n is any integer comprising a supply source for supplying the input wave, means for establishing a beam in said tube, a coding beam interceptor means in said tube having 2^n regions upon which said beam selectively impinges under control of the value of the input wave, beam deflecting means connected to said supply source for effecting said control, each region having n portions having one or another of two characteristics, one of which transmits a portion of the beam and the other of which does not, n electrodes lying beyond said beam interceptor means connected to n output circuits each electrode being conditioned to receive a transmitted portion of the beam, whereby said electrodes are impinged upon by said beam in 2^n permutations, each different, corresponding to said 2^n positions.

7. A tube and associated circuits as per claim 6 having position quantizing means consisting of a supplemental electrode, other beam interceptor means having beam transmitting portions to admit a beam to said supplemental electrode, and feedback means deflectively operative upon said beam to control said beam to cause it to jump from one to another of said 2^n regions in discrete jumps instead of remaining in between any two such regions.

8. In an electron discharge tube, a source of electrons, a target area, means for forming a beam of said electrons and focusing said electrons in a narrow line across said target area, a target located in said target area having a plurality of different types of sub-areas arranged in accordance with a code, means for deriving an output electric condition when said beam falls upon a target sub-area of one type, means for producing a different electric output when said beam falls upon a target sub-area of a different type, signal responsive apparatus means for de-

flecting said line of electrons across said target area at an angle to said line, interconnections between said signal responsive apparatus and said deflecting means for deflecting said beam under control of said signal responsive apparatus.

9. A continuous coding tube for continuously representing the magnitude of an applied signal wave by means of code groups of signaling conditions each of which may be either one or the other of two different electrical conditions comprising a source of electrons, electron beam-forming elements for forming a thin sheet electron beam, a target area, means for directing and focusing said electron beam upon said target area, a target located adjacent said target area having a plurality of sub-target areas each having one or the other of two different responses to impingement of said electron beam thereupon, means for deriving one of said electrical conditions from each of said sub-areas of one type in response to the impingement of said electron beam thereupon, means for deflecting said beam across said target area at an angle to the line of said beam, signal responsive means, and means controlled by said signal responsive means for controlling said deflecting means to deflect said beam of electrons to impinge upon a code group of said sub-areas of said target representative of the magnitude of the applied signal wave.
